DROP HAMMER

Arthur T. Murray, Springfield, Mass., assignor to
 Moore Drop Forging Company, Springfield,
 Mass., a corporation of Massachusetts

Application August 21, 1939, Serial No. 291,151

3 Claims. (Cl. 78—25)

This invention relates to drop hammers, and has particular reference to improvements therein in the matter of lengthening the life of the machine parts and facilitating and improving the accuracy of the adjustment of the registration between the hammer and the anvil.

In accordance with the invention the anvil is provided with a pair of vertical guides, each adjustable in two directions at right angles to each other. The hammer operating mechanism is carried in a frame having a massive foundation entirely separate from that of the anvil. By having the guides carried solely by the anvil they function to guide the hammer vertically into exact registration without reference to any strains that may be imposed upon the hammer actuating mechanism. Conversely, the columns supporting the super-structure which carries the hammer operating mechanism are free from all vibrations resulting from the impact of the hammer on the anvil, and the crystallization of the metal in these columns, which has hitherto been a serious cause of fracture, is avoided.

The manner in which these objects are accomplished will be understood best by references to the accompanying drawings, in which:

Fig. 1 is an elevation, partly broken away in median section, of a drop hammer constructed in accordance with my invention;

Fig. 2 is a sectional detail, on a horizontal plane, of the adjusting mechanism for the hammer guides;

Fig. 3 is a section on line 3—3 of Fig. 1;

Fig. 4 is a section on line 4—4 of Fig. 2; and

Fig. 5 is a side view of the hammer shown in Fig. 1, partly broken away in median section.

The hammer 10 may be carried by a strap or board 11 which is operated by suitable mechanism 9 contained in a super-structure 12. The mechanism may be of any desired type, and it is not necessary to illustrate it here. The super-structure is carried upon vertical frames or columns 13 supported in foundations 14 preferably extending a substantial distance below the ground level 15. These foundations are entirely separate from an intermediate foundation 16 which supports the anvil 17. By making the foundations individually massive and separate one from another, transmission of vibration between them will be greatly reduced from that which would occur were the foundations to be formed in one piece. The columns 13 are thus free from the vibrations set up by the shock caused by the hammer striking the anvil. In prior installations, in which the columns 13 arose directly

from the anvil, the transmission of vibrations through the column from the anvil to the super-structure and back again by reflection has been a serious cause of strain on the columns, leading to crystallization and final fracture. By having the anvil and the columns each terminating in a separate massive foundation, the free flow of vibrations between them is broken up.

The foundation 16 is formed with a cross guideway 20 upon which blocks 21 may slide. Each block 21 is provided with a guideway 22 (Figs. 1 and 4) at right angles to the guideway 20. Slidable in the guideway 22 is a plate 23 supporting vertical channels 24. Each channel is held to its plate 23 by an angle 25 to which it is secured as by smaller angles 26 riveted in place. Each channel has riveted to it at 27 a plate 28 to which is removably secured, as by bolts 29, a plate 30 having a groove 31 formed in its surface and preferably keyed to the plate 28 at 32. The groove 31 operates as a vertical slideway for the hammer 10, and the purpose of making the guide plate 30 removable is to avoid the necessity of replacing the entire channel structure in case the guide becomes so worn that it becomes necessary to replace it.

For moving the blocks 21 on the guideway 20 a screw 35 is threaded through a vertical extension 36 of the base 16 and has a thrust bearing 37 engaging the side of the channel or other part coupled to the blocks. The screw also has an enlargement 38 provided with one or more transverse holes for the reception of a bar by which the screw may be turned. A similar screw 39 is threaded through a block 40 arising from the block 21. Bolts 41 extending through slots 42 in the plates 23 and 25 and similar bolts 43 passing through slots 44 in the plate 23 are threaded into the blocks 21. When the bolts are loosened, the two columns may be moved toward and from each other by the screws 39 and, when the desired adjustment has been reached, may be held permanently by tightening down the bolts 41 and 43. Bolts 45 pass through slots 46 in the plate 23 and the block 21 and are threaded into the anvil. These slots extend at right angles to the slots 42 and 44 and permit the lateral adjustment of the columns by the screws 35.

At their upper ends the columns 24 are joined to horizontal channel members 50 by means of bolts 51 passing through slots 52 to permit the channels being loosened during adjustment and tightened subsequently.

The columns 13 may, if desired, be mounted on guideways 55 and 56 at right angles to each other

in the same manner as channels 54. The same necessity for accurate adjustment is not here present, however, and in general it will not be necessary to provide adjusting screws. Since the construction of the mounting for the columns 13 may be the same as that provided for the hammer guides it has not been shown in detail.

In Fig. 5 is shown a detail of the hammer structure which is of considerable value in permitting adjustment of the hammer blow for different types of work and in compensating for the loss of metal occasioned by the necessity of trimming down the hammer after extended use in order to keep its surface in shape. The board 11 is secured to a wrist pin 60 turning freely on a pintle 61 which itself may turn in a bushing 62 in a hole extending laterally through the hammer. A tapered hole 63 is formed vertically in the upper part of the hammer, preferably traversing the bushing 62. Fitting within each vertical hole 63 is the shank 64 of a heavy weight 65. When the weight is in position it forms a stop for the ends of the pintle 61, so that no extra mechanism need be employed to keep the pintle in position. A threaded hole 66 is provided in the hammer below the shanks 64 so that by inserting a threaded rod in each hole 66 the weights may be forced out of wedging contact with the tapered hole. It will be understood that the weights may be replaced as desired for the adjustment of the weight of the hammer either for particular classes of work or to compensate for wear. When once placed in position the weights wedge themselves firmly in place on the first blow of the hammer and cannot work themselves loose.

I claim:

1. In a drop hammer, an anvil, a massive foun-

dation therefor, guideways extending vertically from the anvil, means permitting the adjustment of each guide in two directions at right angles to each other, a hammer vertically slideable in said guides, means for operating the hammer, columns supporting said operating means, and massive foundations for said columns mounted wholly independently of said anvil foundation.

2. In a drop hammer, an anvil, a massive foundation therefor, a pair of guideways formed on the anvil one on either side thereof, a block movable in each of said guideways, a guideway formed in said block and extending in a direction transverse to the first mentioned guideway, a slide mounted in said second guideway, means for clamping said slides releasably to the anvil, adjusting screws operable when said slides are unclamped to shift the slides accurately, a vertical hammer guideway carried by the second of said slides, a hammer reciprocably mounted in said vertical guideways, operating mechanism for said hammer, columns for supporting said mechanism, and massive foundations for said columns entirely separate from the anvil foundation.

3. In a drop hammer, an anvil, a massive foundation therefor, a pair of vertical members supported from said anvil for adjustment in two directions at right angles to each other, a hammer guideway removably carried by each of said members, a hammer reciprocably mounted in said guideways, operating mechanism for the hammer, a super-structure carrying said mechanism, columns supporting said super-structure, and massive foundations for said columns entirely separate from said anvil foundation.

ARTHUR T. MURRAY.
